CLAIM

The ornamental design for a portion of a display having a graphical user interface with transitional icon, as shown and described.

DESCRIPTION

FIG. 1 is a face view of a portion of a display having a graphical user interface with transitional icon, showing my new design and illustrating a first image thereof.

FIG. 2 is a face view of a portion of the display having a graphical user interface with transitional icon, illustrating a second image thereof.

FIG. 3 is a face view of a portion of the display having a graphical user interface with transitional icon, illustrating a third image thereof.

FIG. 4 is a face view of a portion of the display having a graphical user interface with transitional icon, illustrating a fourth image thereof; and,

FIG. 5 is a face view of a portion of the display having a graphical user interface with transitional icon, illustrating a fifth image thereof.

The appearance of the transitional icon sequentially transitions among the images shown in FIGS. 1-5. The process or period in which any image transitions to another image forms no part of the claimed design.

Subject matter shown in broken lines is environmental and forms no part of the claimed design.
